United States Patent Office.

ALBERT H. SAUNDERS, OF NASHUA, NEW HAMPSHIRE.

Letters Patent No. 81,825, dated September 1, 1868.

IMPROVEMENT IN REEL.

The Schedule referred to in these Letters Patent and making part of the same.

TO ALL PERSONS TO WHOM THESE PRESENTS MAY COME:

Be it known that I, ALBERT H. SAUNDERS, of Nashua, in the county of Hillsborough, and State of New Hampshire, have invented a "new and useful or improved Reel, or apparatus for spooling or winding yarn or thread from a skein;" and I do hereby declare the same to be fully described in the following specification, and represented in the accompanying drawings, of which—

Figure 1 denotes a side elevation, and

Figure 2 a longitudinal section of a reel constructed in accordance with my invention.

Figure 3, a transverse section of it.

The object of my invention is to produce a reel which shall be adapted not only to receive skeins of yarn of different sizes, but one having its arms so constructed that, while they maintain the yarns at a proper degree of tension, either of them may be caused to yield under any undue strain on the yarn, and thereby prevent such yarn from being broken.

In the said drawings, A denotes a base or table, from or near one end of which a standard, B, extends upward in a vertical direction. The said standard B supports a shaft, C, which extends horizontally through it, and is affixed thereto, as seen in fig. 1. On a journal of this shaft a hub, F, is secured, by means of a nut, E.

This hub consists of two recessed or chambered plates, a' b', placed side by side, there being within the chamber c', within such plates, a spiral spring, d', which goes around guide-wheels, e e, and has one end attached to one plate, and the other to the other plate. Stops s s', fixed in the plates a' b', serve, when in contact, to stop the plates, so as to bring, by the draught of the spring, one pair of the arms of the plates into right angles with the other pair. From the said hub a series of radial arms projects, in manner as shown in the drawings, there being a pair of such arms projecting from each of the parts a' b' of the hub. Each of the said arms is formed in two parts, D D', the part D having a cylindrical chamber, b, to receive the part D', which is to slide into and out of the said chamber. Each of the said sliders D' terminates, at its outer end, in a short curved or crescent-shaped bar or plate, c. The lower end of each of the said parts D' rests on a spiral spring, d, which serves to give the slider its required degree of elasticity or movement. Furthermore, each of the said sliders has a chamber or recess, f, cut in it, and formed with two shoulders or abutments, e' e'', the same being as shown in Figure 4, which is a side view of one of the sliders and its crescent-shaped cap. The said recess f is to receive the end of a stud or screw, which is screwed transversely through the said arm D, and into the said recess. The limit of movements of the slider is determined by the length of the recess f, that is, by the stud or screw bringing up against the abutments e' e''.

G denotes a spindle, which projects upward from the base, A, and carries a spool or bobbin, H, upon its upper end, the whole being as shown in fig. 1. This bobbin is to receive the yarn or thread as it is wound from the reel. The winding of the yarn or thread upon bobbins, previous to the weaving of it into cloth, is a well-known requirement, and involves the expenditure of much time. This operation is greatly facilitated by means of my improved apparatus.

In using my improved apparatus, the yarn or thread is to be put upon the reel in the usual manner, and one end of the yarn or thread is to be applied to the periphery of the bobbin; and then the mass of yarn is to be wound on the bobbin in the ordinary way.

The advantage of my improved reel is that it not only allows skeins of different sizes to be reeled upon it, but it maintains them upon the reel with a proper degree of tension, while at the same time, it readily adjusts itself to any inequalities or undue strain upon the threads, which may arise from a knot in the thread, or the crossing of the coils, or a kink in the same. These causes, it is well known, with the ordinary reel, often produce a breakage of the thread and the consequent loss of time. By the use of my machine, this evil is mostly if not entirely remedied.

Furthermore, by making the hub in two parts, connected by a spring, as described, and extending a pair of the arms from each of the said parts, I am enabled to move the arms of one pair toward those of the other, in order to more readily introduce the reel into a skein.

I claim the reel, made with the hub in two parts, a' b', connected by a spring, as described, and having a pair of arms extending from each of the said parts a' b'.

I also claim the reel, as made with the self-adjusting radial arms, and with the hub formed in two parts, a' b', connected by a spring, and having a pair of such arms extended from each of the parts a' b', as specified.

ALBERT H. SAUNDERS.
